UNITED STATES PATENT OFFICE.

LUCIUS FREEMAN LITTLE, OF OWENSBORO, KENTUCKY, ASSIGNOR TO THE ANGLO-AMERICAN MILL CO., OF OWENSBORO, KENTUCKY, A CORPORATION OF KENTUCKY.

PARTITION-RING FOR FLOUR DRESSING AND BOLTING MACHINES.

1,161,487.

Specification of Letters Patent.

Patented Nov. 23, 1915.

Application filed March 1, 1915. Serial No. 11,268.

To all whom it may concern:

Be it known that I, LUCIUS FREEMAN LITTLE, a citizen of the United States, residing at Owensboro, in the county of Daviess and 5 State of Kentucky, have invented new and useful Improvements in Partition-Rings for Flour Dressing and Bolting Machines, of which the following is a specification.

The present invention relates to mills, 10 and particularly to that type of mill in which centrifugal dressers or bolting reels are provided for dressing out the flour, it being common in this type of bolting reel to provide one section with bolting cloth of 15 fine mesh to separate the flour out as a finished product, the rest of the stock passing to the end section of the reel which is provided with fabric of coarser mesh, and in which last-named section the middlings are 20 separated out, while the residue of the stock is tailed over from the reel and subjected, if desired, to further reduction. In mills of 25 this type with the bolting reels divided into flour-separating and middlings-separating sections with fabrics of fine and coarse mesh, it is essential that the products delivered through the reel sections be separated from one another so that the flour may not be commingled with the middlings or coarser 30 materials. It has been proposed to separate the mill into flour-producing and middlings-producing sections by means of partitions which would divide the flour-producing section from the middlings-producing 35 section, but difficulty has been experienced in effectively separating these two sections so that there would be no transfer of middlings products to the flour-producing section.

40 Since the bolting reel is continuous through the two sections of the mill, sealing means must be provided which will effectively prevent this transfer, and the sealing means which I have invented and which I 45 will now describe in detail has proved very efficient in this respect.

In the drawings which accompany and 50 form a part of this specification, I have illustrated one embodiment of my invention, although it will be understood that this is merely illustrative and in no sense restrictive, as the invention may be worked out by means other than those shown without departing from the spirit of my invention.

55 Figure 1 is a longitudinal section of a

bolting reel showing the flour-producing section and the scalper or middlings-producing section at its finishing end. Fig. 2 is a transverse section to show the partition and ring. Fig. 3 is a sectional view of the 60 partition ring. Fig. 4 is a detail view of a slightly different form of the partition ring. Fig. 5 is still another adaptation of my invention. Fig. 6 is a detail view to show the adjustable fabric.

65 Referring to the drawings by numerals, like numbers indicating like parts in the several views, 10 indicates the bolting reel mounted within any suitable mill casing and having the flour-producing section 11 and 70 the scalper or middlings-producing section 12.

The mill is provided with a partition 15 which separates the flour-producing section from the scalper or middlings-producing 75 section, this partition being provided with openings 16 through which the bolting reels pass.

It is obvious that it would be impracticable to fit the reel so closely to the openings 16 as to prevent transfer of flour and middlings products past the partition, and while various expedients have been adopted for sealing the openings, such devices have 80 not met with entire success.

85 According to my invention, I provide the partition 15 with a sealing ring 17 adapted to be secured to the partition and about the reel so as to close the openings 16 and very effectually seal the flour compartment and 90 the middlings compartment from each other. The ring 17 may be made in various ways, but a convenient construction is to provide a rigid body portion formed, as shown, of a plurality of members 18 between which is 95 gripped an annulus of fabric 19 so as to give an inwardly projecting fabric fin which contacts with the covering of silk or other material on the dresser, the contact between the fabric fin and the dresser being intimate 100 enough to prevent any transfer between the flour and middlings compartments.

While in the preferred form the partition ring 17 will be secured to the partition 16 with its fabric annulus in contact with the 105 surface of the bolting reel, it is obvious that this construction might be reversed, and as shown in Fig. 4 the ring 21 may be secured directly to the reel by any suitable fastening means serving to connect it with the 110

metal bars of the reel, and the fabric annulus 22 instead of being placed interiorly of the ring will be arranged on the exterior of the ring 21 so that it will contact with the 5 periphery of the opening 24, as shown in Fig. 4, or it may bear on the side wall of the partition 25, as shown in Fig. 5.

The sections 18 of which the body portion of the ring is formed are preferably held together, as shown, by suitable fastening devices, as screws, so as to firmly clamp the fabric in place, and in order that adjustment of the fabric may be effected so as to compensate for any wear and insure a tightly 15 sealed opening I preferably provide the fabric sections with slightly elongated slots 26 which will permit radial adjustment of the fabric sections to take up any wear which may occur, as shown in Fig. 6.

20 This partition ring is found in practice to very efficiently prevent the transfer of products, and by its use I am enabled to do away with some of the cumbersome devices heretofore used, and among which may be 25 noted an inclosing casing with which it has been proposed to house the scalper in order to prevent this transfer of products.

It will be understood, of course, that variations within the range of mechanical skill 30 may be made from the structure herein illustrated and described without departing from the spirit of my invention.

I claim:—

1. In a bolting reel, the combination with a rotary circular mesh-screened reel having 35 a flour-separating section and a middlings-separating section, of a partition having an opening through which the body of said screened reel extends, and a flexible strip provided about the opening in the partition 40 and adapted to adjust itself to the irregularities in the screened surface of the rotary reel.

2. In a bolting reel, the combination with a rotary circular mesh-screened reel having 45 a flour separating section and a middlings-separating section, of a partition having an opening through which the body of said screened reel extends, and a sectional sealing ring about the opening in the partition comprising a rigid body portion and a circumferentially disposed annulus of fabric 50 removably carried thereby and radially adjustable thereon, said annulus being flexible whereby it may adjust itself to the irregularities in the screened surface of said rotary reel.

In testimony whereof I have hereunto set my hand in presence of two subscribing witnesses.

LUCIUS FREEMAN LITTLE.
